UNITED STATES PATENT OFFICE.

JOHN S. C. NICHOLLS, OF BOSTON, MASSACHUSETTS.

HEATING SYSTEM.

No. 845,371.

Specification of Letters Patent.

Patented Feb. 26, 1907.

Application filed January 27, 1902. Serial No. 91,361.

To all whom it may concern:

Be it known that I, JOHN S. C. NICHOLLS, a citizen of the United States, residing at Boston, in the county of Suffolk, State of Massachusetts, have invented certain new and useful Improvements in Heating Systems, of which the following is a specification, reference being had therein to the accompanying drawings.

10 Figure 1 is a view in the form of a diagram, illustrating one form of my invention. Figs. 2 and 3 show details hereinafter described.

15 My invention relates to heating systems in general, and particularly to hot-water heating systems of that class known as "closed systems."

20 My invention has for its object to improve the construction of closed hot-water heating systems to the end that the pressure may be automatically and perfectly regulated without wastage of heat or water.

25 To these ends my improved heating system comprises a heater, a radiator, supply and return pipes connecting the heater and radiator, an expansion-chamber, a branch pipe communicating at one end with the expansion-chamber and at its other end with the heater, and means controlled by the pressure in the heater for controlling the flow 30 through said branch pipe in both directions and for regulating the heater. By this construction the passage of the water to or from the system through the branch pipe is automatically regulated according to the pressure 35 in the system, while at the same time the action of the heater is also automatically regulated according to the pressure in the system, with the result that the temperature and pressure in the system is automatically maintained below a predetermined point.

40 Other features of my invention are herein-after pointed out.

Having reference to the drawings, 1 represents a heater of any suitable form, and 2 the furnace thereof.

45 3 represents a radiator, one end of which is connected with the upper portion of heater 1 by a supply-pipe 4 and the other end of which is connected with the lower portion of heater 1 by a return-pipe 5. The circulation 50 of the water is from the heater through pipe 4 to radiator 3, through the latter to pipe 5, and through pipe 5 back to heater 1.

Above the heater 1 and radiator 3 is an

expansion-chamber, herein shown as a tank 55 6, connected with heater 1 through a pipe, herein shown as made up of sections 7 and 51, the latter connecting with return 5. In this pipe made up of pipe-sections 7 and 51 is a duplex valve 8, made with a port 9, 60 which is controlled by a check-valve 99, adapted to be opened by pressure from the expansion-chamber and to close by gravity or otherwise when there is no excess pressure from that direction, and made also with a 65 by-pass 10 around valve 99, which by-pass 10 is controlled by a valve 100, whose stem 101 extends through a stuffing-box 81 to the outside of casing 8, where it is pivotally connected at 102 with a lever 103, fulcrumed at 70 104 upon a link 105. Link 105 is pivotally connected at 106 to a lug 82, fast to the cap 83 of the stuffing-box 81. Lever 103 carries at one end an adjustable weight 107, which acts through the lever to hold valve 100 75 against a stop or shoulder 84 in position to close by-pass 10 and in opposition to pressure from below said valve.

When the pressure in the system below valve 100 exceeds that pressure against which 80 weight 107 can hold valve 100 against stop 84, valve 100 will be raised, and as the pressure below valve 100 continues to increase the upward movement of the valve 100 will continue until said valve passes the angle 109 in 85 by-pass 10, when the latter will be open for the passage of water through it, which water will exhaust from by-pass 10 into pipe-section 7, thus crowding the water in section 7 back into tank 6. Thus it will be seen that 90 valve 100 performs the function of a safety-valve and acts to relieve an excess of pressure in the system by automatically opening by-pass 10 when a predetermined pressure exists in the system, so that the surplus water 95 is discharged into the expansion-chamber, made up of pipe 7 and tank 6, and the pressure is thereby maintained below a predetermined point. The purpose of check-valve 99 is to permit water to pass from the expansion-chamber 6, through pipe 7 and conduit 9, into pipe 51, so that that part of the system below valve 9 is kept filled with water from tank 6, said valve acting to close conduit 9 when that part of the system below the valve 105 is filled with water, so that water cannot return to tank 6 except under the conditions described above. Tank 6 is herein shown as

open and is preferably the open flushing-tank of a water-closet, through which water is supplied to the system.

Lever 103 has connected to it one end of a chain 21, the lower end of which is connected with the hinged damper 22 of furnace 2, so that as valve 100 is raised by an increase of pressure below it chain 21 is lowered and damper 22 closed, and furnace 2 thereby regulated so as to reduce the intensity of its heat. When valve 100 descends, damper 22 is opened with the opposite effect upon the furnace.

The distance between shoulder 84 and the angle 109 in by-pass 10 is such as to allow sufficient upward movement of valve 100 to permit valve 100 to entirely close damper 22 before by-pass 10 is opened. Thus in some instances the closing of the damper 22 before by-pass 10 is opened will be sufficient to check a rise of pressure in the system without valve 100 opening by-pass 10. Thus it will be clear that not only does valve 100 act to control by-pass 10, but that through its connection with the furnace it also serves to regulate the latter and to close the damper before it acts as a safety-valve. This valve 100 performing these two functions and combined with the expansion-chamber and valve 99 is an important feature of my invention.

Having now described my invention, without attempting to set forth all of the forms in which it may be embodied or all of the uses to which it may be applied, what I claim is—

1. The improved heating system above described comprising a heater; a radiator; supply and return pipes connecting the heater and radiator; an expansion-chamber; a branch pipe communicating at one end with the expansion-chamber and at its other end with the heater; and means controlled

by the pressure in the heater for controlling the flow through said branch pipe in both directions and for regulating the heater.

2. The improved heating system above described comprising a heater; a radiator; supply and return pipes connecting the heater and radiator; an expansion-chamber; a branch pipe communicating at one end with the expansion-chamber and at its other end with the heater; a check-valve in said branch pipe opening toward the heater; a by-pass around the check-valve; a normally closed valve in the by-pass controlled by the pressure in the system so as to open when a predetermined pressure exists in the latter; and means connected with the normally closed valve for regulating the heater.

3. The improved heating system above described comprising a heater; a radiator; supply and return pipes connecting the heater and radiator; an expansion-chamber; a separate branch pipe connected at one end with the expansion-chamber and communicating at its other end with the heater; a check-valve in said branch pipe opening toward the heater; a by-pass around the check-valve; a normally closed valve in the by-pass controlled by the pressure in the system so as to open when a predetermined pressure exists in the latter, and means connecting the normally closed valve with the damper of the heater for closing the damper before the normally closed valve is opened.

In testimony whereof I affix my signature in presence of two witnesses.

JOHN S. C. NICHOLLS.
